UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,310,595.

Specification of Letters Patent. Patented July 22, 1919.

Application filed November 22, 1917. Serial No. 203,354.

To all whom it may concern:

Be it known that I, JOHN H. BELL, a citizen of the United States, residing at South Orange, in the county of Essex and State of New Jersey, have invented certain new and useful Improvements in Telegraph Systems, of which the following is a full, clear, concise, and exact description.

This invention relates to telegraph systems, and more particularly to telegraph repeating systems.

The principal object of this invention is to provide an improved system for handling so-called half-duplex telegraph service.

In accordance with this invention, messages may be repeated from a duplexed main line to a plain or non-duplexed extension line by means of a line relay and a control relay. In turn, a so-called self-aiding relay is employed for repeating telegraphic signals from the extension line to the duplexed line.

This invention is illustrated diagrammatically in the accompanying drawing, in which only so much of a telegraph equipment has been shown as will be necessary to a clear understanding of the system.

In the drawing, Figure 1 is shown a telegraphic equipment suitable for half-duplex working between two remote substations; in Figs. 2 and 3, respectively, are shown alternate arrangements of the equipment shown in Fig. 1.

Referring to the drawings, a main line indicated by the reference character L extends between two central stations, A and B, from which extension lines 4 connect to branch or substations C and D, respectively. Since a clear understanding of the system may be had by tracing the operations which take place in the transmission of a message, say from the station C to the station D, let it now be assumed that a key switch 2 at the station C is moved to its open position. This operation disconnects the corresponding extension line circuit, which may be traced through a line relay 3, the local contacts of which have not, however, been shown, a line conductor 4, the contacts 11 of a polarized control relay sounder 10, a conductor 14, a winding 21 of a self-aiding polarized pole-changer relay 20, to a grounded current source 9. Cessation of current through the winding 21 of the relay 20 results in the armature of this relay being moved to disconnect a battery 5 from, and to

connect a battery 6 to line L. This operation is set up through a circuit which may be traced from the battery 9, the winding 22 of the relay 20, and a resistance unit 25, to earth. It may be explained that the current normally flowing through the winding 21 is stronger than the current in the winding 22 and therefore the former overpowers the latter current when the line circuit is closed to the station C. Therefore, upon this line circuit being interrupted as described, the weaker current in the coil 22 being unopposed is sufficient to move the armature of this relay to its left-hand position. This operation establishes a circuit which may be traced from the battery 6, over the armature of the relay 20 to the apex or neutral connective point on the polar duplex equipment of the line L, which is intermediate the coils of a polarized line relay 30. From this point current from the battery 6 divides between the left-hand winding of this relay and an artificial line AL to earth, and the right-hand windings of this relay by way of the main line L and the windings of a polar relay 30 and an artificial line AL to earth at the distant central station E. Since the equipments at the points A and C are respectively typical of the equipments at the points B and D, similar reference characters have been employed in designating like parts in all of the equipments. At the station A a portion of the outgoing current from relay 20 may also be traced through a branch or leak circuit formed by a resistance unit 28, a winding 24 of the relay 20, and a resistance unit 26, to earth. At the station B the current as traced through the relay 30 moves the armature thereof to disconnect a battery 7, and to connect a battery 8, through the winding of a polarized relay 10 to earth. The latter relay is thereby moved to separate its contacts 11 and to close its contacts 12. The contacts 11 disconnect the line circuit 4 which extends through a line relay 3 and key switch 2, to earth at the substation D. At this moment, a circuit may also be traced from the battery 9 and the winding 21 of the polarized relay 20, the contacts 12 of the relay 10, and a resistance unit 13, to earth. At the relay 10, the action is such that the contacts 12 engage in advance of the separation of the contacts 11. It will, therefore, be obvious that in addition to opening the line circuit

to the station D, the relay 10 also substitutes the resistance 13 for the circuit to that station, in order that the circuit will not be interrupted through the winding 21 of the relay 20, whereby the armature of the latter relay will be retained in circuit with the battery 5. On the sending key 1 at the station C being closed, current through the winding 21 of the relay 20 at A overpowers the effect of current through the winding 22 of this relay, whereupon its armature will be moved to engage the battery 5 and current therefrom will transverse the circuits already traced, to oppositely bias the relay 30 at B, which accordingly connects the source of current 7 through the relay 10. This current being of opposite polarity to the current traced from the battery 8, it will oppositely bias the relay 10, which thereupon establishes its contacts 11 and separates its contacts 12, thereby disconnecting the resistance unit 13 and substituting therefor the extension line 4 of the substation D, in a manner similar to that already described. In moving to its opposite position, the armature of the relay 10 closes its contacts 11 before its contacts 12 are separated; therefore, no interruption of current through the winding 21 of the relay 20 at B takes place and the armature of this relay is accordingly held on its normal bias to engage the source of current 5.

From the foregoing description, it will be clear that in response to the key 1 at the substation C, the relay 20 at A will establish changes of current polarity over the line L to correspondingly operate the line relay 30 and in turn the local control relay 10 at the station B, and that such operation of the relay 10 establishes opening and closing of the extension line 4, whereby the line relay 3 and local sounder equipment controlled thereby (not shown) at the substation D, will respond in translating a message.

Directing attention to the vibrating or self-aiding feature employed with the pole changer relays 20, a circuit may be traced from a grounded condenser 27 through windings 23 and 24 of this relay, and a resistance unit 26, to earth. This condenser will be charged by either the battery 5 or the battery 6, depending upon the position of the relay armature; and it will furthermore be obvious that on the instant the armature of the relay 20 separates from either one of its contact stops and before arriving at the opposite contact stop, the condenser 27 will discharge over the series circuit already traced through the windings 23 and 24 of this relay. The relation of this current action through the latter windings with respect to the windings 21 and 22, is such that discharges from the condenser 27 will be in phase with the respective action of current through the winding 21 or 22, and thereby serve to aid

respectively the latter windings in moving the armature of this relay. The proportions of the winding 24 and the resistance 26 are such that the direct current present at any moment therethrough, will be in a direction 70 to relieve the polarizing or biasing effect on the relay armature. It may be pointed out, however, that on the instant the armature establishes either one or the other of its circuits, the condenser 27 will receive a charge 75 through the winding 23 which will set up action differential to or neutralizing with respect to the direct current through the winding 24, thereby permitting the armature to establish a sufficiently long interval of contact in responding to current through either the winding 21 or 22 in the relations already described.

In telegraph working it is frequently necessary to effect a so-called "break," whereby 85 a receiving operator may interrupt the sending operator in order to transmit in the opposite direction. In describing break service, as carried out by the present system, let it now be assumed that while a message is 90 under transmission from the substation C, that an operator at the substation D may have occasion to interrupt the message. The key switch 2 at D is accordingly moved to its open position, thereby disconnecting a 95 circuit which extends from the battery 9 at B through the winding 21 of the relay 20, whereupon current through the winding 22 causes the armature of this relay to establish the battery 6 with the outgoing connective 100 point on the duplexed equipment of the main line L. At the station A, the line relay 30 responds to this current and connects the battery 8 through the winding of the polarized control relay 10, to earth. Contacts 11 are opened while the contacts 12 are closed at the latter relay, thereby opening the circuit of the line 4 to the substation C and substituting therefor the resistance unit 13, in order that the relay 20 may be retained in 105 its normal position as already described. Cessation of operation of the line relay 3 and its local sounder (not shown) at C, indicates a break signal to the operator at that point; the key switch 2 will therefore be moved to its closed position, thereby permitting the operator at D to transmit to the station C in a manner similar to that already described in connection with transmission from the station C to the station D. 120

Since the equipment at the two ends of the main line L is identical, as already mentioned, it will be clear that message signals and break signals may be effected from one end of the line in a manner identical with the operations for the same service in the opposite direction.

Referring to Fig. 2 of the drawing, while this alternate arrangement provides that service results, similar to those already de- 130

scribed in connection with Fig. 1, may be attained, the operations are carried out in a slightly different manner. For convenience of description, however, characters of reference similar to those employed in the arrangement already described have been used in designating like or correspondingly operating parts in the alternate arrangement.

- 10 Although only a repeater equipment is shown at A and a substation equipment is shown at C, it will be understood that a main line L extends to a distant repeater station at which an equipment similar to that shown 15 at A is employed in connection with equipment at a second substation typical of the substation C. For purpose of description, let it be assumed that a message is under transmission from the substation C by way 20 of the main line L to the distant substation. In response to operation of the transmitting key 1, interruptions will be effected in a circuit which may be traced through the line relay 3, line conductor 4, the contacts 11 of 25 the relay 10, the conductor 14, the windings 21 of the relay 20, to the battery 9. The relation of the windings 21 and 22 of this relay are the same as the relation of the same windings in the corresponding pole changer 30 relays already described, in connection with Fig. 1. Therefore, in response to opening and closing of the line 4, the armature of the relay 20 will be rocked to alternately connect the sources of current of 5 and 6 35 with the line L, thereby setting up operations at the distant repeater stations which are translated into the extension line of the distant substation. In order to accelerate the operation of the pole changer relay 20, 40 its windings 23 and 24 are connected and operate in a manner similar to the corresponding windings on the self-aiding pole changer relays already described in connection with Fig. 1.
- 45 In describing the operations whereby an incoming message may be received at the substation C, changes of current polarity established in the line L by a distant transmitter in a manner similar to the polarity 50 changes already described, as set up in transmitting from a substation C, will cause the armature of the polar relay 30 to be moved to alternately connect the sources of current 7 and 8 through the winding of the control 55 relay 10. At the instant the armature of the relay 30 is connected with the battery 8, the armature of the polar relay 10 will be biased to its opposite or negative position, thereby separating its contacts 11 and 12, and closing 60 its contacts 15. The time relation of the contacts 11 and 15 are such that the latter contacts will be closed in advance of the separation of the contacts 11 and vice versa. Disconnection of the contacts 11 opens the 65 circuit of the line circuit 4 to the substation

C, while separation of the contacts 12 disconnects winding 22 of relay 20. A circuit may also be traced from the battery 5, and armature of the relay 20, through the resistance unit 28, winding 23 of this relay, 70 contacts 15 of the relay 10, and a resistance unit 13, to earth. It will be clear that the described operation of the relay 10 substitutes current through the winding 23 and the resistance unit 13 for current normally 75 established through the winding 21 of this relay and the substation line 4. The connective relation between the coils 21 and 23 is such that the circuit changes at the relay 10 do not permit the relay 20 to operate, the 80 current through the winding 23, acting in the same direction on the armature as the current previously flowing through its winding 21. On responding to a correspondingly poled impulse of current from the line L, 85 the armature of the relay 30 connects with the battery 7, whereupon the relay 10 will be oppositely biased to close its contacts 11 and 12 and to separate its contacts 15, thereby completing a circuit from the battery 9 90 through the winding 21 of the relay 20 to the substation line 4, and also to restore the normal connection through the winding 22 in substitution of the connection through the winding 23 of the relay 20. In this manner, 95 incoming impulses from the line L are repeated into the substation line 4.

In order to initiate a break signal from the station C to interrupt an incoming message, a key switch (not shown), similar to the 100 switch 2 shown in Fig. 1, will be moved to its open position, thereby opening the line 4 and causing cessation of current through the winding 21 of the relay 20. Current present through the winding 22, which may 105 be traced from the source 9, contacts 12 of the relay 10, and the resistance unit 13, to earth, thereupon moves the armature of the relay 20 into engagement with the battery 6, thereby establishing an outgoing impulse of 110 negative current with the duplexed line L, which on arriving at the distant station, operates a polar relay corresponding with the line relay 30, and in turn a control relay, as the relay 10 to interrupt the line to the associated substation. These operations take 115 place in a manner similar to the operations already described in connection with the receipt of a message at the station C.

In describing the alternate arrangement 120 shown in Fig. 3 of the drawing, it will be understood that equipment typical of that shown at A and C may be present at a corresponding distant central and substation on the line L. Therefore, in tracing outgoing message signals from the substation C, an open position of the transmitter key 1 disconnects a circuit which may be traced through the line relay 3, contacts 11 of a control relay 10, a conductor 14, the wind- 125 130

ing 21 of a pole changer relay 20, to a source of grounded current 9. Cessation of current in the winding 21 permits the current present in the winding 22 to move the armature 5 of this relay to disconnect the battery 5 and to connect the battery 6 to the split or outgoing connective point on the duplexed line L. At the distant station this current from the line operates a corresponding line relay, as the relay 30 and a control relay, as the relay 10, to open the circuit of the extension line to the substation at that point. During moments the key 1 at substation C is closed, current in the winding 21 of the relay 20, over the circuits just traced, overpowers the current in the winding 22, thereby returning the armature to disconnect the battery 6 and to connect the battery 5 to the line L. The resulting action at the distant end of the line is to oppositely bias the line relay and the control relay at that point and thereby close the extension line to the associated substation.

In tracing the operations whereby messages from the distant substation are received at the substation C, let it be assumed that in response to a change of polarity in the line L, the line relay 30 will be moved to its opposite bias, thereby connecting a battery 8 through the control relay 10. The armature of the latter relay will be thereby moved to separate its contacts 11 and to close its contacts 12. The time relation of these contacts is such that the contacts 12 will close before the contacts 11 separate and vice versa, for an opposite movement of the armature. Closure of the contacts 12 establishes a circuit which may be traced from the battery 5 over the armature of the relay 20, a resistance unit 28, the winding 23 of relay 20, a conductor 16, the contacts 12 of the relay 10, and a resistance unit 13, to earth. Due to the operating time relation of the contacts of the relay 10, as already described, a current through the winding 23 is established before cessation of current through the winding 21 of the relay 20, and the polarity relation of this circuit change is such that the armature of the relay 20 will be retained in its normal position connecting with the battery 5. The circuit changes set up by the relay 10, substitute the winding 23 for the winding 21 in establishing a circuit to overpower the effect of current through the winding 22 and also the effect of the small accelerating current present in the winding 24 of the relay 20. An impulse of current from the line L of opposite polarity, will move the armature of the relay 30 to establish the battery 7 through the relay 10, thereby returning the armature of the latter relay to its normal position to close the contacts 11 and to separate the contacts 12. In this position the circuit of the line 4 to the sub-

station is completed through the winding 21 of the relay 20 over the circuits already traced while the direct current circuit through the winding 23 of the latter relay is interrupted, all in a manner to not affect 70 the normal position of its armature.

It will, therefore, be clear that for the receipt of messages from the line L, the relays 30 and 10 at the repeater station and the relay 3 and associated sounder at the 75 substation are active while the pole changer relay 20 at the repeater station continues inert.

The self-aiding effect at the pole changer relay 20, is substantially the same for the 80 corresponding relay in each figure of the drawing, the resistance of the units 28 and 26 being such that the current strength over the leak circuit through the relay winding 24, will be small compared with the portion 85 of the currents which branch through the line relay 30 in the transmitting of messages outgoing over the duplexed line L.

It may also be mentioned that the characteristics of the windings 23 and 24 and 90 the resistance unit 26 as well as condenser 27 are such that the discharge of this condenser will best meet the phase relation of the current changes set up by the transmitter key at the associated substation. It 95 may be further pointed out that the equipment shown at A and C in Fig. 1 may be located at one end of a line circuit and operated with equipment similar to that shown at A and C in either of the Figs. 2 and 3, 100 and further that the equipment shown in Fig. 2 may be employed at one end of a line to work in connection with equipment similar to that shown in Fig. 3 at the opposite end of a main line.

105

What is claimed is:

1. In a telegraph system, a first line section, a second line section, sources of current employed with equipment comprising a line relay, a control relay operated by said line relay to repeat messages in one direction between said line circuits, and a self-aiding relay rendered operative jointly by said line and said control relay for repeating telegraphic messages between said lines in the 115 other direction.

2. In a telegraph repeater system, a first line section and a second line section, sources of current employed with equipment comprising a line relay and a control relay for 120 repeating telegraphic signals from said first to said second line section, a self-aiding relay for repeating telegraphic signals from said second to said first line section, and means operated by said control relay for 125 rendering said self-aiding relay either operative or non-operative.

3. In a telegraph repeater system, a first and a second line section, sources of current employed with equipment comprising relay 130

means for repeating telegraphic signals from said first to said second line section, self-aiding relay means comprising a plurality of operative circuits, and means controlled by said first mentioned relay means to render the operative circuits of said self-aiding relay effective to repeat signals from said second to said first line.

4. In a telegraph repeater system, a plurality of line circuits, sources of current employed with equipment comprising relay means for repeating signals between said line sections in one direction, other relay means for repeating signals between said line circuits in an opposite direction, self-controlled circuits and externally controlled circuits for said last mentioned relay means, and means controlled by said first mentioned relay means to substitute a self-controlled circuit for an externally controlled circuit of said second mentioned relay means to effect locking of the latter relay.

5. In a telegraph repeater system, a first line section, a line relay for said first line, sources of current employed with equipment comprising a second line section, a control relay for said second line, means for rendering said line relay and said control relay effective to repeat signals from said first to said second line section, self-aiding relay means, self-controlled circuits for said self-aiding relay means, externally controlled circuits for said self-aiding relay means, means for rendering said self-aiding relay effective to repeat signals from said second to said first line section, and means

operated by said control relay to substitute a self-controlled circuit for an exteriorly controlled circuit of said self-aiding relay means to establish locking of the latter relay. 40

6. In a telegraph repeater system, a plurality of line sections, sources of current employed with equipment comprising means for repeating telegraphic signals in one direction between said line sections, a self-aiding electroresponsive means for repeating telegraphic signals between said line sections in an opposite direction, self-aiding circuits and exteriorly controlled circuits for said self-aiding electroresponsive means, and means controlled by said first mentioned means for substituting a self-aiding for an exteriorly controlled circuit for locking said self-aiding electroresponsive means. 45

7. In a telegraph repeater, a first line section, a second line section, sources of current employed with equipment comprising electroresponsive means for repeating telegraphic signals from said first to said second line section, self-aiding relay means for repeating telegraphic signals from said second to said first line sections, a local circuit means, and means controlled by said electro-responsive means for substituting said local circuit means for said second line section in retaining said self-aiding relay means in its normal position. 50

In witness whereof, I heretunto subscribe my name this 20th day of November, A. D. 1917.

JOHN H. BELL.
